UNITED STATES PATENT OFFICE

109,716

DESIGN FOR AN INCANDESCENT LAMP

George Kende, New York, N. Y., assignor, by
mesne assignments, to Universal Camera Cor-
poration, New York, N. Y., a corporation of
Delaware

Application March 30, 1937, Serial No. 68,479

Term of patent 14 years

To all whom it may concern:

Be it known that George Kende, a citizen
of the United States, and resident of New York
city in the county of New York and State of
New York, has invented a new, original, and
ornamental Design for An Incandescent Lamp,
of which the following is a specification, refer-
ence being had to the accompanying drawing
forming part thereof, in which,

Fig. 1 is a side elevational view of an incan-
descent lamp embodying my design;

Fig. 2 is a top plan view thereof; and

Fig. 3 is a bottom plan view thereof.

The dominant feature of the design is in the
ornamental ribs or corrugations near the outer
end of the lamp bulb in association with the pro-
portions thereof and the flange element and base
of the lamp.

I claim:

The ornamental design for an incandescent
lamp substantially as shown and described.

GEORGE KENDE.
